FIG. 2 -

FIG. 3 -

Inventor
Henry W Lormor

Russ Hudson & Kent
Atlys.

UNITED STATES PATENT OFFICE.

HENRY W. LORMOR, OF CLEVELAND HEIGHTS, OHIO, ASSIGNOR TO WILLARD STORAGE BATTERY COMPANY, OF CLEVELAND, OHIO, A CORPORATION OF WEST VIRGINIA.

COUNTERBALANCED COVER.

Application filed October 8, 1927. Serial No. 225,000.

This invention relates to improvements in counterbalanced covers, and finds special utility when applied to tanks and vats for use in handling paints, acids and chemicals of various kinds in manufacturing plants.

Containers of the sort mentioned commonly have separable covers which are movable bodily toward and away from the container either by counterbalancing mechanism or by a crane. Such mechanism is cumbersome and is apt to be in the way of the workmen and to interfere with the use of overhead handling systems for the articles to be treated in the container.

One of the objects of my invention, therefore, is the provision of a counterbalanced cover attached to the container capable of movement from closed to open position and vice versa without any considerable effort even in the case of very heavy covers, and adapted to remain in either closed or fully open position without the use of a lock or latch.

A minor object is the provision of means for automatically increasing the leverage of the power means acting upon the cover as the latter approaches wide open position.

Other objects and features of novelty will appear as I proceed with the description of that embodiment of the invention which, for the purposes of the present application, I have illustrated in the accompanying drawings, in which:

Fig. 1 is an end elevation of a vat or the like equipped with a counterbalanced cover built in accordance with my invention, the cover being shown in closed position;

Fig. 2 is a view on a smaller scale similar to Fig. 1 but showing the cover in partially opened position;

Fig. 3 is another view similar to Fig. 1 but with the cover in wide open position;

Fig. 4 is a detail side view of a guide bracket which may be employed in connection with the invention; and

Fig. 5 is a rear view of the bracket shown in Fig. 4, that is, a view looking in the direction of arrow 5 in Fig. 4.

Similar reference characters refer to like parts throughout the views.

In the drawings I have indicated at 10 a container which may be a vat for acid or other chemicals or any other type of tank or box, although the invention will be most useful

in connection with containers of large size. 55 The cover of the container is shown at 11. It is here illustrated as provided with two or more reenforcing and supporting angle irons 12 to which the cover is connected by any convenient means. The angle irons 12 extend 60 beyond the rear edge of the cover 11 and crosswise of supporting brackets 13 which are mounted upon the rear wall of the container. These brackets carry hinge pintles 14 which extend through the angle irons 12 and upon 65 which the cover swings.

On the upper side of the rear extremity of at least one of the angle irons 12, I secure a guide bracket consisting of an angular piece of metal 15 with a curved upper end, as 70 shown, and a channelled guide bar 16. The upstanding arm of the angular member 15 is longer than the base arm, for a purpose which will hereinafter appear. A coil spring 17 is attached at its lower end to an angle 75 bracket 18 on the container 10 or to any other fixed connection. Its upper end is attached to a flexible connecting member, such as a chain 19, adapted to rest within the channelled guide 16 and extending over the curved 80 end of said guide, being there attached to an eye bolt 20 which protrudes through a hole in an angle bracket 21. A nut 22 on the end of the bolt serves to draw up the chain and thereby control the tension of the spring 17. 85 Any suitable means may be employed to prevent the cover from swinging back of its vertical position. For this purpose, I have shown a stop 23 mounted in bracket 13 (see Fig. 3).

In describing the operation of the invention, we will consider that the entire mass of the cover is located in its center of gravity and the letter W on the drawings indicates this mass. The power pull of the spring 17 will be designated P. The leverage through which gravity acts upon W is indicated by the letters B, B' and B'' in Figs. 1, 2 and 3 respectively, while the leverage through which the spring pull P acts is marked A, A' and A'' in those figures. The spring 17 is so selected and its tension so regulated that in the closed position of the cover B x W is least as great as A x P, and preferably B x W is somewhat greater so that not only friction 100 in the hinges but gravity as well tends to hold the cover in closed position. When the operator desires to open the container, he

grasps the forward edge of the cover and swings it up until the leverage through which gravity acts upon the cover is reduced to such an extent that $A \alpha P$ becomes greater than 5 $B \alpha W$. The angle through which the cover must be swung in order to shift the advantage to $A \alpha P$ can be varied within rather wide limits, but I prefer to have the critical position about that illustrated in Fig. 2, where 10 $A' \alpha P$ is greater than $B' \alpha W$. Hence, after causing the cover to pass the position indicated in Fig. 2 moving upwardly, the operator may, if he desires, let go of the cover, whereupon it will of itself move into the position 15 of Fig. 3. In the latter position, $A'' \alpha P$ is considerably greater than $B'' \alpha W$, and hence the cover is quite positively held in open position. This effect is increased by the fact that the leverage A'' is controlled by the long 20 arm of the guide bracket piece 15, while in all positions between Figs. 1 and 2 this leverage remains fairly constant, being controlled by the short arm of the bracket piece 15.

Having thus described my invention, I 25 claim:

1. In combination, a cover, a horizontal hinge therefor located to one side of the center of gravity thereof, and means acting upon the cover on that side of the hinge which 30 is opposite said center of gravity tending to move the cover from horizontal position toward vertical position, said means overbalancing the action of gravity upon the cover and friction in the hinge only after the 35 cover has been swung upwardly upon its hinge away from horizontal position.

2. In combination, a receptacle, a substantially horizontal cover therefor, a hinge for said cover near one extremity thereof, and 40 means acting upon the cover tending to open it, said means overbalancing the action of gravity upon the cover and friction in the

hinge only after the cover has been swung upwardly upon its hinge a predetermined distance. 45

3. In combination, a cover, a horizontal hinge therefor located to one side of the center of gravity thereof, and power means acting upon said cover through the leverage of a power arm tending to move the cover from horizontal position toward vertical position, the length of said power arm being 50 automatically increased as the cover approaches vertical position.

4. In combination, a cover, a horizontal hinge therefor located to one side of the center of gravity thereof, a spring tending to move the cover from horizontal position toward vertical position, said spring working over a guide bracket on the cover having unequal arms, the leverage of the spring being controlled by the long arm when the cover is in substantially vertical position and by the short arm when the cover is in substantially 55 horizontal position.

5. In combination with a container, a cover hinged thereto, power means on one side of said hinge tending to lift said cover into open position, the product of the power means times its leverage being no greater than the 70 product of the mass of the cover times its leverage when the cover is in closed position.

6. In combination, a receptacle, a substantially horizontal cover therefor, a hinge for said cover near one extremity thereof, and means acting upon the cover tending to open it, said means being incapable of lifting the cover from closed position, being capable of balancing the cover in a partly open position, and being capable of overbalancing the cover in a fully open position. 75

In testimony whereof, I hereunto affix my signature.

HENRY W. LORMOR.
